CLAIM

We claim the ornamental design for a mobile computing device, as shown and described.

DESCRIPTION

FIG. 1 is a first perspective view of mobile computing device;

FIG. 2 is a second perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines are directed to environment and are for illustrative purposes only. The broken lines form no part of the claimed design.
